UNITED STATES PATENT OFFICE.

JARED BURTON, OF WHEATON, MINNESOTA.

BLANKET-HOLDING ATTACHMENT FOR VEHICLES.

SPECIFICATION forming part of Letters Patent No. 739,286, dated September 22, 1903.

Application filed June 27, 1903. Serial No. 163,371. (No model.)

To all whom it may concern:

Be it known that I, JARED BURTON, a citizen of the United States, residing at Wheaton, in the county of Traverse and State of Minnesota, have invented a new and useful Blanket-Holding Attachment for Vehicles, of which the following is a specification.

The invention relates to an improved storm-blanket or apron-holder for buggies, carriages, and other vehicles, and has for its object to provide a simple, inexpensive, and efficient device of this character which may be quickly attached to a vehicle and by means of which the apron or blanket may be securely retained in position at all times.

A further object of the invention is to provide an apron-holder which may be readily adjusted to vehicles of different widths and capable of holding the blanket in such a position as to cause the rain and sleet to be deflected and drain over the sides of the vehicle, thereby completely protecting the occupants.

A further object is to provide a holder adapted to be clamped to the bed of the vehicle and capable of being adjusted to and from the dashboard and raised or lowered to suit the occupants of the vehicle and which may be readily converted into a holder for securing the dust robe or boot in position on the carriage.

The invention consists in the construction and novel combination and arrangement of parts hereinafter fully described, illustrated in the accompanying drawings, and pointed out in the claims hereto appended, it being understood that various changes in the form, proportion, and minor details of construction may be resorted to without departing from the spirit or sacrificing any of the advantages of the invention.

In the accompanying drawings, Figure 1 is a perspective view of a portion of a buggy, showing my improved robe or blanket holder applied thereto. Fig. 2 is a transverse sectional view showing the blanket or robe in position on the carriage. Fig. 3 is a similar view showing the device adjusted and used

for holding the dust robe or boot in position. Fig. 4 is a detail longitudinal sectional view, and Fig. 5 is a transverse sectional view of the clamping members.

Similar numerals of reference indicate corresponding parts in all the figures of the drawings.

1 designates a portion of a vehicle—a buggy in the present instance—to the opposite sides of the bed of which are attached in any suitable manner supporting-brackets 2. Secured to the angular arms 3 of the supporting-brackets is a slotted bar 4, through which passes a bolt 5, a wing-nut 6 engaging the threaded end thereof and by means of which the bar may be adjusted and clamped at any desired angle with relation to the bracket. The abutting faces of the bar and bracket are roughened or serrated, as shown, to form gripping-surfaces. The ends of the slotted bars 4 are provided with circular heads 7, pivotally supported between the forked ends 8 of supporting-arms 9, the opposite ends of said arms being slotted, as shown at 10, and fitting in recesses or sockets 11, formed in the side face of a clamping member 12. The arms 9 and recesses 11 are provided with serrated faces 13, as shown, said arms being adjustably secured in the recesses or sockets by means of a bolt 14, which passes through one of a series of openings 15 in the clamping member 12 and also through the slot 10 in said arms, and by means of which the arms are adjusted to fit vehicles of different widths. The clamping member 12 is formed in two sections pivoted together, as shown at 16, the end of the pivot-pin 17 being threaded and adapted to receive a clamping-nut 18. The upper surface of the two sections comprising the clamping member 12 is provided with longitudinally-disposed ribs or corrugations 19, and secured to said sections are correspondingly ribbed or corrugated clamping-plates 20, the apron or blanket 21 being introduced between the plates 19 and clamping member 12 and secured in position by means of screws 22, passing through said plates and clamping member.

When it is desired to attach the holder to a buggy or other vehicle, the brackets 2 are secured to the bed of the vehicle slightly in rear of the foot-rail, as clearly shown in Fig. 1 of the drawings, after which the arms 9 may be adjusted to the width of the bed by loosening the bolts 14 and sliding said arms forward or backward, as the case may be. The apron or blanket is then inserted between the plates 20 and the member 12 and clamped in position by tightening the screws 22, and the two sections comprising the clamping member swung upwardly on the bars 4 by loosening the clamping-nut 18, forming in effect a watershed and permitting the rain and sleet to drain from the blanket 21 over the sides of the vehicle, as clearly shown in Fig. 2 of the drawings. The supporting member may be raised or lowered or adjusted to or from the dashboard by loosening the nuts 6 and adjusting the bars 4 at the desired angle with relation to the bracket.

When it is desired to use the holder for supporting a dust robe or boot, the supporting arms 9 and clamping member 12 are swung downwardly until they assume a horizontal position, as illustrated in Fig. 4 of the drawings, after which the boot may be secured in position in the manner before described.

From the foregoing description it will be seen that I have provided an exceedingly simple, inexpensive, and effective holder by means of which a storm blanket, robe, or apron may be securely retained in such a position on a vehicle as to cause the rain and sleet to be deflected and which, by reason of its peculiar construction, may be readily raised or lowered and adjusted at any angle or inclination to suit the occupants.

Having thus described my invention, what I claim is—

1. An apron-holder for vehicles comprising, a pair of vertically-adjustable clamping members extending transversely across the vehicle and means for supporting said members.
2. An apron-holder for vehicles comprising, a pair of vertically-adjustable pivoted clamping members extending transversely across the vehicle and means for supporting said members.
3. An apron-holder comprising, a pair of vertically-adjustable pivoted clamping members extending transversely across the vehicle, arms adjustably secured to said members, and means for supporting said arms.
4. An apron-holder comprising, a pair of vertically-adjustable clamping members, arms adjustably secured to said members, means for supporting said arms and a pivotal connection between the arms and the supporting means.
5. An apron-holder comprising, a pair of vertically-adjustable pivoted clamping members, arms adjustably secured to said mem-

bers, means for supporting the arms, and a bar adjustably secured to the supporting means and pivotally secured to the arms.

6. An apron-holder for vehicles comprising, a pair of clamping members, arms adjustably secured thereto, a pair of brackets, and a pivotal connection between the arms and the brackets. 70

7. An apron-holder for vehicles comprising, a pair of clamping members, arms adjustably secured thereto, a pair of brackets, and a bar pivotally connected to the arms and adjustably secured to the brackets. 75

8. An apron-holder for vehicles comprising, a pair of pivoted clamping members, arms adjustably secured thereto, a pair of brackets, and a pivotal connection between the arms and the brackets. 80

9. An apron-holder for vehicles comprising, a pair of pivoted clamping members, arms adjustably secured thereto, a pair of brackets, and a bar pivotally connected to the arms and adjustably secured to the brackets. 85

10. An apron-holder for vehicles comprising, a pair of pivoted clamping members, recesses or sockets formed therein, arms adjustably mounted in said recesses or sockets, a pair of brackets, and a pivotal connection between the arms and the brackets. 90

11. An apron-holder for vehicles comprising, a pair of pivoted clamping members, auxiliary clamping-plates carried by said members, arms adjustably secured to the clamping members, a pair of brackets, and a pivotal connection between the arms and the brackets. 95

12. An apron-holder for vehicles comprising, a pair of pivoted clamping members, auxiliary clamping-plates carried by said members, arms adjustably secured to the clamping members, a pair of brackets, and a bar pivotally connected to the arms and adjustably secured to the brackets. 105

13. An apron-holder comprising, a pair of vertically-adjustable pivoted clamping members, auxiliary clamping-plates carried thereby, the adjacent faces of the clamping members and auxiliary clamping-plates being roughened or corrugated, means for supporting the clamping members, and a pivotal connection between the supporting means and said clamping members. 110

14. An apron-holder comprising, a pair of vertically-adjustable clamping members, a hinged connection between said members, a threaded pin passing through the adjacent ends of the hinged members, a nut engaging the threaded end of said pin, arms adjustably secured to the clamping members, a pair of supporting-brackets, and a slotted bar adjustably secured to the brackets and pivotally secured to the arms. 120

15. An apron-holder comprising, a pair of vertically-adjustable clamping members, recesses or sockets formed therein, a hinged 130

connection between said members, a pair of slotted arms fitting within the recesses or sockets and adjustably secured therein, auxiliary clamping-plates carried by the clamping members, a pair of brackets and a slotted bar adjustably secured to the brackets and pivotally connected to the arms.

In testimony that I claim the foregoing as my own I have hereto affixed my signature in the presence of two witnesses.

JARED BURTON.
